DESIGN FOR A COAT

Hyman Frost, New York, N. Y.

Application July 3, 1940, Serial No. 93,427

Term of patent 3½ years

To all whom it may concern:

Be it known, that I, Hyman Frost, a citizen of the United States, residing in New York city, in the county of New York and State of New York, have invented a new, original, and ornamental Design for a Coat, of which the following is a specification, reference being had to the accompanying drawing, forming part thereof.

Fig. 1 is a front view of a coat showing my design;

Fig. 2 is the left side view of Fig. 1, and
Fig. 3 is the right side view of Fig. 1.
The rear of the coat is conventional.
I claim:
The ornamental design for a coat, substantially as shown and described.

HYMAN FROST.
